TABLE AND ROOM DIVIDER

William R. Keck, Chicago, Ill., assignor of fifty percent to Jean Rea, Chicago, Ill.

Application January 24, 1956, Serial No. 560,955

2 Claims. (Cl. 311—2)

This invention relates to convertible furniture and particularly to a combined room divider and table.

An object of the invention is to provide an attractive room divider capable of being extended to various sizes, but regardless of the extension size of the divider, retaining the table part thereof in readiment for use.

Another object of the invention is to provide a room divider which includes a main, center section from which extension panels are easily pulled to the desired positions with respect to the main, center section.

A further object of the invention is to provide a room divider as described above wherein there is a table top inset within the main body section so that with the front part of the main body section it constitutes an attractive panel the table top forming portion of which is capable of being extended to the operative, horizontal position.

A further object of the invention is to provide an adjustable room divider that has extensible panels together with a table top which cooperate to form an attractive article of furniture.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a perspective view of a preferred embodiment of the invention;

Figure 2 is a perspective view of the embodiment in Figure 1 showing the same in the extended, usable position as not only a table but also a room divider;

Figure 3 is a perspective view of another preferred embodiment of the invention;

Figure 4 is a longitudinal sectional view taken on the line 4—4 of Figure 2 and in the direction of the arrows;

Figure 5 is a sectional view taken on the line 5—5 of Figure 3 and in the direction of the arrows;

Figure 6 is an enlarged fragmentary sectional view taken on the line 6—6 of Figure 1 and in the direction of the arrows;

Figure 7 is an enlarged sectional view taken on the line 7—7 of Figure 1 and in the direction of the arrows;

Figure 8 is a fragmentary sectional view taken on the line 8—8 of Figure 5 and in the direction of the arrows;

Figure 9 is a fragmentary elevational view of the table in the extended, usable position; and

Figure 10 is a fragmentary side view of a modification wherein the legs are of a type to more steadily support the combined table and room divider.

The room divider 10 which typifies the invention is of lightweight construction so that it may be easily moved from one place to another. The divider 10 is intended to be a decorative and attractive article of furniture. Accordingly, it may be made of various woods or finished in a variety of ways. One of the more attractive finishes is a covering of an attractive cloth-like material. There

2

are numerous cloths which may be used including some of the available plastics.

The structural makeup of the room divider includes pairs 12 and 14 of generally V-shaped, bar stock legs 5 whose ends are connected to the center body section 16 of the divider. Other leg constructions may be substituted. For example (Figure 10) the legs 13 and 15 connected by a brace 17 constitute a pair attached to one end of body section 16. They are secured to section 15 quite high thereon and diverge at the bottom, in order to have a firmer leg base for the combined divider and table. If desired wheels or casters 19 may be used at the lower ends of legs 13 and 15. Moreover, legs 13 and 15 may be connected to the unshown legs at the opposite side of section 16 by cross members.

The center section 16 comprises an upper strip 18, a lower strip 20 and sides 22 and 24. A back panel 26 is secured to the sides, the top and the bottom strips by standard fasteners. Reinforcing angles 30 are secured to 10 the corners of the sides, bottom and top strips in order to rigidify the entire structure. A front panel 32 is secured to the bottom strip 20, the front edge of the top strip 18 and to the sides 22 and 24 in order to form the box-like center section 16.

An extension panel 38 is mounted in the center section 16 and is movable laterally of the center section 16 through a slot 40 which is formed in the side 22. Panel 38 is formed of lightweight material, as fiber board of various types and is upholstered with a covering 42. Upper rollers 44 are secured to the back panel 26, and to a dividing panel 48 located between the back panel 26 and a second dividing panel 50 in the center section 16. A seat of lower rollers identical to those at 44 are mounted in the bottom of the passage 52 which is defined by the back panel 26 and the divider 48. By virtue of this construction the extension panel 38 is easily moved inwardly or outwardly of the center section 16.

Another panel 54 is slidable in passage 56 which is formed between the divider 48 and the divider 50. Panel 54 is movable through a slot in the side 24 of the center section and is mounted on the lower and upper rollers 58 which are identical to the rollers 44. Panel 54 may be upholstered as at 60 in the same manner as panel 38.

A pair of vertical plates 63 and 64 are secured to the sides 22 and 24 by means of screws or the like and are held spaced therefrom by means of laterally projecting spacers at the upper and lower ends thereof. This forms a pocket behind each plate. Each plate has a vertical slot in it, the slot 65 being in plate 63 while the slot 66 is in the plate 54.

The plates 63 and 64 with the slots therein form a portion of the means for mounting the table 68 in the main center section 16. Front panel 32 has an aperture in it of the same size (approximately) as the table 68, and the table 68 is normally at rest therein fitting flush with the front upholstered surface of the front panel 32. Table 68 has a spindle 70 secured to the bottom surface of it. The ends of the spindle have caps 72 thereon, these caps 55 being located in the spaces behind the plates 63 and 64, the spindle 70 passing through slots 65 and 66 therein. Accordingly, the spindle 70 is captive in the slots and is capable of vertical movement. Therefore to withdraw the table 68 from within the aperture in front panel 32 60 (Figure 5) the finger grip strip 74 is pulled outwardly permitting gravity to lower the table 68 while the spindle 70 slides downwardly in the slots 65 and 66. At the full lowered position the table 68 is horizontal and spindle 70 rests upon the lower ends of the slots 65 and 66. Such slot ends are located immediately above the spacer 76 65 which is secured to the front panel 32 and the divider 50.

in order to rigidify and strengthen the structure at this point.

A pair of legs 80 suitably strengthened and supported are mounted pivotally on hangers 82 on the undersurface of the table 68. A brace 84 extending pivotally from each leg 80 has its outer end disposed in a bayonet latch 86 which is secured to the undersurface of table 68. Therefore when the table 68 is in the closed position as shown in Figure 5 the legs 80 together with all of the structure apertinent thereto is folded under the table 68 and is located behind the table 68. Upon withdrawal of the table from the center section 16 the legs 80 are extended to the operative position and latched. Then the table is ready for use.

Although the table 68 may be made of a one piece construction, for economy of weight it may be built up by utilizing a rectangular frame 88 having front and rear panels 89 and 90. Metallic or plastic trim molding 94 extends around the rectangular table 68 and retains the upholstery layers 95 thereon.

If it is found desirable a decorative cap 96 may be placed on the top of the center section 16 and upholstered together with the remainder of the center section. Choices of upholstering material and color are left within the prerogative of the designer.

In use one or both of the panels are extended in order to provide privacy or to function as a room or area divider for any other purpose. When it is desired to use the divider as a table, the table 68 is pulled downwardly as described previously. When it is desired to use the divider merely as a room divider, the table 68 is placed onto the center section 16 as shown in Figure 1. It is noted that in either case full adjustment of either or both of the panels 38 and 54 is unaffected.

It is understood that various modifications may be made without departing from the claimed invention. For example, the room divider may be materially embellished with decorative attachments. The tapered panel 99 is hinged to one side of the room divider 10 as shown in Figure 3. It is understood that such a panel may be applied to the other side of the divider 10. When the tapered panel is used on one side only of the room divider, the opposite edge may be placed against the wall. Other such modifications may be made.

What is described as new is as follows:

1. A combined room divider and table comprising a main section having sides, a bottom, a top and a front wall, said section having chambers, said sides having en-

trances for said chambers, an extension panel mounted in each chamber and movable between the extended and retracted positions through said entrances, anti-friction supporting means for said panels and disposed in said

5 chambers, a table, said section front wall having an aperture in the top part thereof, said table disposed in said aperture and fitting flush with said front wall to provide a part of one wall of one chamber when said table is fitting flush with the remainder of said front wall, said section having a pair of slots which open into said aperture, a pivot connected with said table and located in said slots for attaching said table to said section and constraining the movement of said table with respect to said section so that said table is capable of being extended and 15 returned into said aperture.

2. Combination furniture comprising a center section that has a back wall, a front wall, side walls, a top wall, and a bottom, said walls and bottom enclosing a chamber, said sides having entrance slots that register with said

20 chamber, extension panels movable through said entrances to extend and return positions in said chamber, said front wall extending upwardly from said bottom only partially toward said top wall thereby leaving an aperture in said front wall, a spacer behind said front wall and in said 25 chamber and helping to retain said front wall fastened in place and separated from said panels in said chamber, inwardly opening longitudinal slots in said chamber and located above said spacer and near said aperture, a combination table and partial front for said section, said combination table and partial front movable between open and closed positions which are respectively with said table fitting in said aperture and flush with said front wall and extended laterally from said front wall, and means connected with said table at the inner edge thereof and engaged in said slots for constraining the movement of said 30 table between the open and closed positions.
